DISPENSING DEVICE

Abraham S. Schenker, Brooklyn, N. Y.

Application September 18, 1934, Serial No. 744,531
Renewed January 18, 1937

4 Claims. (Cl. 312—77)

This invention relates to dispensing devices and particularly to dispensing devices for elongated articles such as tooth picks, matches, cigarettes and the like.

5 The principal object of the invention is to provide an improved device of this class wherein one end of the article dispensed is raised out of the receptacle or container for holding a number of the articles, so that it can be conveniently 10 taken hold of. Another object is to provide an article of this class which is neat and attractive in appearance, convenient in operation and of low cost.

15 The preferred form of my improved dispensing device is illustrated in the drawing accompanying and forming part of this specification. In the drawing,—

Figure 1 is a side elevation of the preferred embodiment of my improved dispensing device.

20 Fig. 2 is a front elevation of the same.

Fig. 3 is a plan of the same.

Fig. 4 is a side elevation of the same, partly in section, showing parts in different positions from those of Fig. 1.

25 Fig. 5 is a transverse section taken on the line 5—5 of Fig. 1, and

Fig. 6 is a detail plan of part of the container or receptacle for the articles dispensed.

In the drawing the numeral 2 denotes the base 30 member, 3, 3 are pivot supports mounted thereon and extending upwardly, and 4, 4 are suitable pivots in said supports. Preferably the pivots and supports are mounted in a member 5 of sheet metal provided with projections 6. The base member is preferably of some material which can 35 be formed around said projections 6 for securing the member 5 to said member 2. The member 2 may be formed of any suitable material such as Celluloid, Bakelite, metal such as that used for die castings, or other suitable material.

40 There is a container or receptacle 7 pivoted on the pivots 4 by pivotal elements 8. The latter are located preferably not far from one end of said container 7, near its upper edges. The said container has a two part top cover 9, the rear part 9a being pivoted to the container at 10, and the front part, indicated by 9b, being hinged to 9a at 9c. The part 9b is preferably of transparent material. There is an under cover or trailer 11 hinged to the top cover and the container by means of the small rod or wire 10a. The under cover 11 has a tapered slot, such as 12, in its forward part centrally disposed between the side edges of said cover and normally disposed to swing downwardly.

Also pivoted on the pivot supports 3 is an operating member or lever 14 which is preferably provided with pivotal portions 15, an upright portion 16, a handle portion 17, an actuating portion 18, a rear stop portion 19, and a front stop portion 20. The actuating portion 18 contacts with the rear end of the container 7 and causes the same to move when the member 14 is oscillated.

The container 7 is preferably rectangular in plan and its bottom is formed by two portions 21 sloping downwardly from the sides 22 of the container toward the middle part. It has a slot 23 in its middle part, toward the front wall 24, and said slot has extensions 25 at the sides. On 15 the member 5 is formed an upright portion 26 which I term the selector, and at the upper part of the selector are projections 27, which when seen from the front, form a Y or fork in which a match, tooth pick, cigarette or the like can 20 rest. The extensions 25 of the slot 23 permit the container 7 to be assembled with the selector 26, the projections 27 being passed therethrough. Mounted on the under side of the top cover part 9b is a cover prop 28 having a fork 25 or V-shaped slot 29 in alinement with the selector 26.

To operate the device, the container 7 is supplied with articles to be dispensed, such as tooth picks, matches etc., and these are placed lengthwise therein as at t. The container 7 being in its lowermost position or that of Fig. 1, the handle portion 17 of the member 14 is moved forward or to the position shown in Fig. 4, when the stop portion 20 prevents further movement in that direction. The container 7 will be moved by the portion 18 so as to raise its forward end. A tooth pick or article to be dispensed will be caught by the fork or Y of the selector 26, and upon downward movement of the container caused by rearward movement of the member 14, the forward part of the tooth pick in the Y will remain up and projecting through the slot 12 of the under cover 11. The cover prop 28 is arranged so as 45 to rest on the tooth pick immediately in front of the parts 27 of the selector thus causing the top cover to be raised to the position in Fig. 1. Thus the article to be dispensed is in a convenient position to be taken hold of and removed 50 from the container.

The arrangement of the portion 20 of the operating member 14 is such that movement forward by means of the handle portion 17 tends to stabilize the device. In other words it prevents ten- 55

dency to overturn the device when the handle is operated.

The under cover 11 normally has its front end on the articles dispensed and tends to lightly

5 press them downward except at the middle part of the container where they can be readily moved through the slot 12 by means of the projections 27 or Y of the selector 26. Both covers can be raised when placing articles in the container.

10 What I claim is:—

15 1. A dispensing device comprising a base member having two spaced container pivoting elements mounted thereon and extending upwardly, a movable container pivoted to said elements adjacent one of its ends and having a longitudinal slot in the bottom part adjacent its opposite end, an upper cover pivoted to the container at the latter's pivotal end, an under cover pivoted to the upper cover pivot and having a slot in its 20 free end adapted to align the articles to be dispensed, a selector mounted on the base member in alinement with said under cover slot and having its upper portion extending through said longitudinal slot, and means to actuate the container on its pivots.

25 2. A dispensing device comprising a base member having two spaced container pivoting elements mounted thereon and extending upwardly, a movable container pivoted to said elements adjacent one of its ends and having a longitudinal slot in the bottom part adjacent its opposite end, said bottom part being so formed that the articles to be dispensed collect over said slot, an upper cover pivoted to the container at the latter's pivotal end, an under cover pivoted to the upper cover pivot and having a slot in its free 30 end adapted to align the articles to be dispensed, a selector mounted on the base member in aline- 35

ment with said under cover slot and having its upper portion extending through said longitudinal slot, and means to actuate the container on its pivots.

3. A dispensing device comprising a base member 5 having two spaced container pivoting elements mounted thereon and extending upwardly, a movable container pivoted to said elements adjacent one of its ends and having a longitudinal slot in the bottom part adjacent its opposite end, an upper cover pivoted to the container at the latter's pivotal end and provided with an element to assist in alining the articles to be dispensed, an under cover pivoted to the upper cover pivot and having a slot in its free end adapted 10 to align the articles to be dispensed, a selector mounted on the base member in alinement with said under cover slot and having its upper portion extending through said longitudinal slot, and means to actuate the container on its pivots. 15

4. A dispensing device comprising a base member having pivoting means, an oscillating container pivoted near one end to said means and provided with means for aligning articles to be dispensed said container having a slot in its bottom adjacent the other end, an upper cover pivoted at its rear end to the upper part of the container and adapted to be opened by the articles to be dispensed, a movable under cover pivoted to one end of the container, the lower 20 part of said cover adapted to rest on and align the articles to be dispensed, a fixed selector on the base member aligned to the aligning means on said cover and container and adapted to pass through said slot to eject an article on downward 25 oscillation of the container, and means to actuate the container on its pivoting means. 30
